UNITED STATES PATENT OFFICE.

CHARLES H. GROFFMAN, OF SYRACUSE, NEW YORK.

SUPPORT FOR ELECTRIC FIXTURES.

1,131,059.

Specification of Letters Patent.

Patented Mar. 9, 1915.

Application filed May 8, 1913. Serial No. 766,380.

To all whom it may concern:

Be it known that I, CHARLES H. GROFFMAN, of Syracuse, in the county of Onondaga, in the State of New York, have invented new and useful Improvements in Supports for Electric Fixtures, of which the following, taken in connection with the accompanying drawings, is a full, clear, and exact description.

This invention relates to certain improvements in supports for electric fixtures and is adapted to be used more particularly in connection with what is commonly known as "knob and tube work" for electrical wiring of buildings as distinguished from conduit work or that class in which the wires are passed through pipes or conduits. In the conduit work, the ends of the pipes are usually equipped with outlet or junction boxes in the side walls or ceiling of the building and constitute sufficient support for the electric fixtures, but, in the "knob and tube work" special provision has to be made for the support of the electroliers or other fixtures and, owing to the lack of uniformity in selecting this class of supports, it is left entirely to the discretion of the electrician who is installing the work and, in many instances, is found to be unreliable and more or less dangerous from improper securing or liability of short circuits.

The main object is to provide a more reliable means for supporting electric fixtures in buildings where conduit-wires and junction boxes are not employed, and at the same time to permit the fixture with its wires properly connected and insulated from each other to be easily and quickly installed or removed as a unit. In other words, I have sought to produce a simple, compact and comparatively inexpensive fixture support having a sufficiently wide range of adjustment to enable it to be standardized and adopted more universally than any of the present widely varying methods.

Another object is to construct the fixture support in such manner that the lath and plaster may be finished flush with the lower side of the base of said support, so that the fixture and wire connections are always accessible by simply sliding the usual canopy downward.

A further object is to secure the electric fixtures and insulators for the binding posts upon a single bar which may be attached to or detached from the base by the movement

of a single fastening member, thereby permitting the insulator and fixture to be properly secured to said bar before the latter is installed and, at the same time, allowing the bar to be firmly secured to the base and the binding post connected to the supply wires with the assurance that the fixture is safely secured and the wires properly connected.

Other objects and uses will be brought out in the following description.

In the drawings—Figure 1 is an inverted plan of a device embodying the various features of my invention. Fig. 2 is a longitudinal sectional view of the same device as secured to a pair of joists. Figs. 3 and 4 are perspective views of fragmentary portions of diametrically opposite sides of the fixture-supporting base showing the means for interlocking the fixture supporting bar therewith. Fig. 5 is a detail sectional view through one of the insulators and its supporting bar.

This fixture support comprises a strut —1— and a base —2— having a detachable fixture-supporting bar —3— carrying a pair of insulators —4— and an electric fixture —5—, the insulators —4— being adapted to receive and support separate sets of wire clamping members or binding posts —6—.

The strut —1— may be made of cast metal or stock steel bars of sufficient length to span the maximum standard distance between the joists or studs of the building so that its ends may be secured by suitable fastening means as screws —7— to the underside of the joists or studs as —a—, Fig. 2. This bar is of substantially the same thickness as an ordinary lath and is provided with a continuous lengthwise slot —9— through the greater portion of its length to receive the bolts or screws —7—, also suitable attaching means as bolts or studs —10— by which the base —2— is attached thereto, thereby allowing the box to be adjusted longitudinally practically the entire distance between the joists or length of the bar to conform to the desired position of the fixture —5—.

The intermediate portion of the bar between the joists —a— is preferably disposed in a plane at one side of but parallel with the ends a distance corresponding approximately to the thickness of the lath, the object of which is to permit the use of a base as 2 of substantially the same thickness or depth as the combined thickness of the lath and plaster which may

be indicated respectively by the reference letters —*b*— and —*c*—, thereby allowing the plaster to finish flush with the lower face of the base.

- 5 The base 2 preferably consists of a cylindrical cup-shaped member of cast metal or equivalent material secured in an inverted position to the under side of the strut —1— and its fastening means as the bolts —10—
- 10 passing through the slots and provided with ends whereby the base 2 may be firmly clamped in its adjusted position, the bolts —10— being disposed diametrically opposite each other and equi-distant from the center of the base so as to give the entire device a symmetrical and balanced appearance.

The upper closed side of the box is preferably provided with a pair of tubular bosses —11— for receiving the current-supply wires as —*d*— which are brought downwardly through said bosses and fastened to the binding posts —6— by one set of screws thereon, the other set of screws, one for each insulator, serving as a means of attachment for the ends of the fixture wires as —*e*—.

- The periphery of the base is substantially smooth and cylindrical while its interior is provided with diametrically opposite bar-retaining members —14— and —15— formed integral therewith and producing with the closed side of the base radial recesses or slots —16— and —17—. The slot —16— is permanently closed at both ends while the slot —17— is permanently closed at one end, only the opposite end being removed but is replaced by a movable detent —18— consisting of a screw entering a threaded aperture in the adjacent portion of the base. These retainers —14— and —15— and their slots —16— and —17— constitute means for receiving and supporting the opposite ends of the fixture-supporting bar —3— which may be made of cast metal or equivalent material and is preferably of relatively narrow width as compared with the diameter of the base but still of sufficient width to form a substantial support for the fixture —5—, the ends of said bar being practically the same but of slightly less width than the slots —16— and —17— which they are adapted to enter.

The central portion of the base —3— is depressed below, but in a plane substan-

tially parallel with that of its ends to allow ample space below the top of the base for the passage of the wires from the fixture to the binding posts. In placing this bar in operative position, the screw —18— is first loosened and one end of the bar is then inserted in the slot —16— after which the opposite end of the bar is drawn into the slot —17— through its open side whereupon the screw —18— is tightened in operative position to firmly hold the bar against accidental displacement.

The object in providing the bar —3— with opposite diverging sides is to receive the insulators —4— and to support them a sufficient distance apart from each other and from the fixture to reduce the liability of short circuits due to carelessness in connecting the wires and also to facilitate adjustment or readjustment of the wires after the fixture is in place by simply loosening the canopy —*f*— and sliding it downward. It will also be observed that by removing the screw —18— and disconnecting the supply wires from the binding posts, the bracket —3— and entire fixture attached thereto and supported thereby may be removed from the base.

What I claim is:

1. In a support for electric fixtures, the combination of a hollow base, a fixture-supporting bar removably mounted within and upon the base and having its central portion depressed below its ends and provided with means for attaching a fixture, insulators secured to said bar at opposite sides of said fixture attaching means, and binding posts for supply and fixture wires mounted on the insulators.

2. In a support for electric fixtures, the combination of an inverted cup-shape base, a cross-bar within the base and movable relatively thereto, means for holding the bar in operative position on the base, said bar having central attaching means for a fixture, insulators on the bar at opposite sides of the fixture attaching means, and binding posts for the fixture wires secured to the insulators.

In witness whereof I have hereunto set my hand this 5th day of May, 1913.

CHARLES H. GROFFMAN.
